UNITED STATES PATENT OFFICE

JOHN B. PAGIN, OF SOUTH BEND, INDIANA

DESIGN FOR A FISHING LURE

Application filed November 13, 1931. Serial No. 41,712. Term of patent 14 years.

To all whom it may concern:

Be it known that I, JOHN B. PAGIN, a citizen of the United States, residing at South Bend, in the county of St. Joseph and State of Indiana, have invented a new, original, and ornamental Design for Fishing Lures, of which the following is a specification, reference being had to the accompanying drawing, forming a part thereof.

Figure 1 is a top plan view of a fishing lure showing my new design.

Figure 2 is a view in side elevation of the fishing lure.

Figure 3 is a bottom plan view of the fishing lure.

The dominant feature of the design is the scalloped contrasting coloration between the front and rear ends of the lure body.

I claim:—

The ornamental design for a fishing lure as shown and described.

JOHN B. PAGIN.
